UNITED STATES PATENT OFFICE

127,512

DESIGN FOR AN ELECTRICAL APPLIANCE PLUG CONNECTOR

Clifford Brooks Stevens, Fox Point, Wis., assignor
to Cutler-Hammer, Inc., Milwaukee, Wis., a
corporation of Delaware

Application March 3, 1941, Serial No. 99,334

Term of patent 14 years

To whom it may concern:

Be it known that I, Clifford Brooks Stevens, a citizen of the United States and a resident of Fox Point, in the county of Milwaukee and State of Wisconsin, have invented a new, original, and ornamental Design for an Electrical Appliance Plug Connector, of which the following is a specification, reference being had to the accompanying drawing, forming part thereof.

Figure 1 is a front elevational view showing one face of an electrical appliance plug connector incorporating my new design.

Fig. 2 is a side elevational view thereof.

Figs. 3 and 4 are top and bottom plan views, respectively, of said connector.

Fig. 5 is an enlarged fragmentary sectional view on the line 5—5 of Fig. 1.

Fig. 6 is an enlarged fragmentary sectional view on the line 6—6 of Fig. 1.

Fig. 7 is an enlarged fragmentary sectional view on the line 7—7 of Fig. 1.

I claim:

The ornamental design for an electrical appliance plug connector, substantially as shown.

CLIFFORD BROOKS STEVENS.
